UNITED STATES PATENT OFFICE.

HENRY BLAND, OF WAVERLEY, NEW SOUTH WALES, AUSTRALIA.

ELASTIC-FLUID COMPRESSOR.

SPECIFICATION forming part of Letters Patent No. 760,843, dated May 24, 1904.

Application filed April 20, 1903. Serial No. 153,546. (No model.)

To all whom it may concern:

Be it known that I, HENRY BLAND, a subject of the King of Great Britain, and a resident of Ashley street, Waverley, near Sydney, in the State of New South Wales and Commonwealth of Australia, have invented certain new and useful Improvements in and Relating to Elastic-Fluid Compressors, of which the following is a specification.

This invention relates to improvements in the cylinders, pistons, and valves of elastic-fluid compressors; and it has been designed with the primary objects of more completely effecting the cooling of the compressed elastic fluid and of making better provision for the action of the valves. I accomplish these objects by the novel construction and arrangement of the cylinders, pistons, and valves, by means of which the elastic fluid is sprayed while being compressed and the cylinder and cylinder-head maintained cool by the constant circulation around them of water or other cooling medium.

I am aware that heretofore various arrangements have been proposed for the cooling of the compressor-cylinders, chiefly by circulating water in a jacket or jackets surrounding the cylinders; but by my invention I utilize practically the entire surface of cylinder and cylinder-head for cooling purposes, leaving less interposing metal than hitherto between the cooling medium and the heated gas. I am aware also that it has been proposed to spray the elastic fluid under compression by means of force-pumps or other expenditure of power.

In order that the invention may be clearly understood, reference is made to the accompanying drawings, in which—

Figure 1 is a sectional elevation, and Fig. 2 a plan, of my improvements, while Figs. 3, 4, and 5 are transverse sections through the lines A A, B B, and C C, Fig. 1, respectively.

The same numerals refer to the same parts throughout.

The cylinder-barrel 1 is provided on its inner periphery with spiral grooves 2, formed in the cylinder-casting, within which is a thin liner 3. The cooling medium enters at the inlet 4 and flows through the spirally-formed

passage to the outlet 5, thus bringing the cooling medium closer than heretofore to the heated gas and rendering the cooling more effective. The cylinder-head 6 is formed to meet the purpose of an emission-valve and is provided with a hollow neck 7, passing through a suitable stuffing-box 8 and gland 9 in the bonnet or cover 10, thus permitting a free vertical movement.

11 is a spring for the purpose of returning the head or valve to its seating.

The neck 7 has a central inlet-pipe 12, with a concentric pipe or passage 13 to permit the waste cooling-water to flow upward to discharge. The body of the head 6 has a spiral groove or channel 14 behind its lower face 15, the said groove being fed from the central inlet-pipe 12, the waste water passing out through the passage 13 in the neck. The lower face 15 of the head is comparatively thin and is approximately conical for the purpose hereinafter explained.

The internal spray is operated by a plunger 16, fixed to the lower face 15 of the cylinder-head. The said plunger has perforations at 17 in communication with a central passage 18, provided at its lower end with a small ball-valve 23 for suction purposes. A barrel 19 for the plunger is screwed centrally in the compressing trunk-piston, leaving spaces for suitable packing 21, and at its lower end is a back-pressure valve 22 and flexible supply-pipe. The compressing-piston is a composite one formed of a body part 24 and an outer sleeve 25, provided with the usual piston-rings 26, fitting the cylinder-barrel. At its lower edge is a screwed-in ring 27 for regulating the extent of the opening between the said body and sleeve. The body 24 of the piston is formed to fit within the sleeve 25, and it has eyes 28 for the wrist-pins 29 of the connecting-rods, which are placed well up in the piston, as shown clearly in Fig. 1. The upper edge 30 of the piston-body forms, with the lip 31 of the sleeve 25, the intake-valve. When the intake-valve is closed, the face of the piston is flush with the lip 31.

32 represents air-passages leading to the intake-valve.

The face 33 of the piston is dished conically

to correspond with the lower face of the cylinder-head.

34 is the compressed-air outlet leading to receiver.

5 The operation of my improved apparatus is as follows: When the piston fully recedes, the barrel 19 is filled with water, preferably by gravity, from a tank at a higher elevation than the perforations 17, which water is retained 10 in the barrel by the back-pressure valve 22, which closes at the completion of the descent. On the upstroke of the piston the barrel ascends on the plunger 16 and forces the water up the small central passage 18 and through 15 the perforations 17 and is thus sprayed into the volume of elastic fluid under compression. Cool water from a storage-tank or other source enters the inlet 4 in the cylinder-barrel and flows around the spiral passage formed by the 20 grooves 2 to the outlet 5, while water passes down the pipe 12 and circulates through the spiral channel 14 in the cylinder-head. The cylinder-head has a slight upward movement sufficient to permit delivery of the compressed 25 charge. On the downstroke of the piston the body 24 moves first within the sleeve 25 to the extent permitted by the screwed ring 27, and thence carries the sleeve with it throughout the stroke. On the return stroke the piston-body then moves upward within the sleeve, and thus closes the opening of the intake-valve. The face of the piston is dished, so that at about the completion of the compression stroke the cylinder-head comes into contact with any surplus of water between the two 35 faces, the water being put into motion without "hammer."

A great advantage of my construction is the facility afforded for inspection of the interior 40 parts. It will be seen that by raising the bonnet the cylinder-head and the plunger may be lifted out clear of the other parts of the apparatus.

Having now described my invention, what 45 I claim as new, and desire to secure by Letters Patent, is—

1. In an apparatus for compressing an elastic fluid, the combination with a cylinder and cylinder-head, of a hollow plunger fixed to the 50 cylinder-head and disposed centrally in the cylinder, a trunk-piston arranged to reciprocate in the cylinder for compressing the fluid, a barrel movable with the trunk-piston and inclosing the hollow plunger, said hollow plunger being provided with spraying-perforations 55 adjacent to the cylinder-head, and means for introducing water into said barrel behind the plunger, substantially as described.

2. In an apparatus for compressing an elas-

tic fluid, the combination with a cylinder and 60 piston, of a cylinder-head movable toward and from a seat in the end of the cylinder, means for yieldingly holding the cylinder-head to its seat, a bonnet fixed to the cylinder over the 65 cylindrical head, a hollow neck fixed on the head and movable therewith endwise in a stuffing-box on the bonnet and open at its outer end, a water-inlet pipe arranged concentrically within said neck, and a spiral groove formed in said cylinder-head and communicating 70 at one end with said inlet-pipe and at its other end with a passage communicating with the space between the inlet-pipe and the hollow neck, substantially as described.

3. In an apparatus for compressing an elastic fluid, the combination with a cylinder, of a conical cylinder-head movable toward and from a seat in the end of the cylinder, a spring for yieldingly holding the cylinder-head to its seat, a bonnet fixed to the cylinder over the 80 cylinder-head, an outlet leading from the cylinder between said head and bonnet, a hollow plunger rigid with said head and disposed centrally within the cylinder, a trunk-piston arranged to reciprocate in the cylinder for compressing the fluid and having a concave face corresponding to the conical shape of the cylinder-head, a barrel movable with the trunk-piston and movably fitted on said plunger, said 85 hollow plunger being provided with spraying-perforations adjacent to the cylinder-head, and means for introducing water into the barrel behind the plunger, substantially as described.

4. In an apparatus for compressing an elastic fluid, the combination with a cylinder and 90 cylinder-head, of a piston arranged to reciprocate in the cylinder and comprising an outer sleeve provided at one end with an inwardly-projecting annular lip and at its other end with an inwardly-projecting adjustable collar, the hollow piston-body open at one end and fitted within said sleeve and having a limited movement between said lip and collar, air-passages in the outer periphery of the body of 95 the piston and extending at one end to the interior of the piston and at the other end to the edge of the piston-body adjacent to the said lip, the said collar being screwed into the inner end 100 of the sleeve, whereby the movement of the hollow piston in the sleeve may be regulated, 105 substantially as described.

In witness whereof I have hereunto set my hand in presence of two witnesses.

HENRY BLAND.
